(57) **CLAIM**

The ornamental design for a mouse mover as shown and described.

DESCRIPTION

FIG. 1 is a perspective view of a mouse mover showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 of FIG. 1.

The large dash broken lines seen in the figures represent the extents of the enlarged portions, and form no part of the claim. All other broken lines in the figures depict portions of the mouse mover that form no part of the claimed design
